UNITED STATES PATENT OFFICE.

ROBERT E. CREAMER, OF WORCESTER, MASSACHUSETTS.

PIPE-CUTTING WRENCH.

1,215,623.

Specification of Letters Patent. Patented Feb. 13, 1917.

Application filed May 27, 1916. Serial No. 100,334.

To all whom it may concern:

Be it known that I, ROBERT E. CREAMER, a citizen of the United States, residing at Worcester, in the county of Worcester and State of Massachusetts, have invented a new and useful Pipe-Cutting Wrench, of which the following is a specification.

This invention relates to a pipe cutting wrench and particularly to means for operating the cutting disk of the wrench.

The object of my invention is to provide a simple and efficient means for moving one of the cutting disks inwardly and outwardly within the wrench occupying a minimum amount of space and the least possible exertion on the part of the operator.

With these and other objects in view my invention consists in a novel combination and arrangement of parts hereinafter described and more specifically pointed out in the appended claim.

In the accompanying drawings I have shown my invention sufficiently to enable those skilled in the art to understand the construction and operation thereof.

Referring to the drawings:

Figure 1 is a side view of my improved pipe cutting wrench; in this view a portion of the frame is broken away.

Fig. 2 is a view corresponding to Fig. 1, but shows some of the parts in a different position.

Fig. 3 is a sectional plan view taken on line 3—3, Fig. 2, viewing in direction of arrow *a*, same figure.

Fig. 4 is a detached plan view of the cutter slide, operating screw and connecting parts; in this view the slide is shown in section, and,

Fig. 5 is a detail view of the wrench operating handle.

In the accompanying drawings 10 is the main frame having slidably mounted therein a dovetail slide member 11; said slide 11 has secured in the upper portion thereof a stud 12, upon which is loosely mounted the cutter disk 13.

A lead screw 14 is loosely mounted in suitable bearings in the frame 10, said screw 14 being retained in its horizontal position by means of the screw 15 mounted in the frame 10, the inner end of said screw 15 engaging a recess 14^a in the screw 14.

The screw 14 has formed therein right and left hand threads 16 and 17, said threads

16 and 17 engaging the screw collars 18 and 19 respectively.

Secured in an upwardly extending projection 18^a, of the collar 18 is a stud 20 upon which is loosely mounted one end of a connector 21; the opposite end of said connector 21 is loosely mounted on a stud 22 secured in the slide 11.

Secured in an upwardly extending projection 19^a, of the collar 19, is a stud 23 upon which is loosely mounted one end of a connector 24, the opposite end of which is loosely mounted on the stud 22 secured in the slide 11.

A bevel gear 25 is secured on the screw 14, said gear 25 meshing with a like gear 25 secured on a stud 27 mounted in a suitable bearing 10^a of the frame 10.

Loosely mounted on studs 29 and 30, secured in the frame 10, are the disk cutters 28 and 28^a.

I have provided a socket wrench 31 having a square opening 31^a in one end thereof; the opposite end 31^b of said wrench being square in cross section to engage like openings 10^b in the frame 10.

I will now briefly describe the operation of the above mentioned parts:

The frame 10 which is of C shape is placed over the pipe A, the square recess 31^a of the wrench 31 is then applied to the most convenient square end 14^a or 27^a, the screw 14 is then revolved thus causing the screw collars 18 and 19 to travel toward each other, this, as will readily be seen, through the connectors 21 and 24, forming a toggle, will cause the slide 11 to be carried upwardly until the cutting disks 13, 28 and 29 engage the periphery of the pipe, see Fig. 1.

The frame 10 is then revolved around the pipe by means of wrench being used as a lever, the end 31^a being applied to the square ends 14^a and 27^a or the opposite end 31^b of the wrench 31 being inserted into the openings 10^b of the frame 10 as it is revolved about the pipe A.

At intervals the screw 14 is revolved as above described, causing the disks 13, 28 and 29 to engage deeper into the body of the pipe A, see Fig. 2, and the operation repeated until the pipe is severed.

It will readily be seen and appreciated by those skilled in the art that I have provided a simple and efficient device by which

a pipe may be severed as for instance to sever a pipe at a desired point that is already installed in a trench where the working space is limited.

5 Having thus described my invention it is evident that certain changes and modifications may be made therein by one skilled in the art without departing from the spirit and scope thereof, therefore, I do not wish 10 to be limited to the specific details herein disclosed, but what I claim is:

A pipe cutter of the type described, including a carrying frame having an arm equipped with rotary cutters and opposed 15 to, and spaced from the base of said carrying frame, a driven right and left hand threaded screw having bearings in said frame, a slide- able member positioned in said carrying frame, opposite the cutter-equipped arm of

said carrying frame, and equipped with a 20 rotary cutter arranged with respect to the cutters of said arm, collars having threaded connections with said right and left hand threaded screw, and pivoted-together toggle-link connection between said collars, the 25 pivot between the links of the latter connection also pivoting in said slideable cutter- carrying member, and a screw and annular recess connection between said carrying frame and said right and left hand threaded 30 screw.

In testimony whereof I have hereunto set my hand, in the presence of two subscribing witnesses.

ROBERT E. CREAMER.

Witnesses:

ERNEST R. LLEWELLYN,
CHARLES S. WEBSTER.
